(57) **CLAIM**

The ornamental design for a leather lace bracelet, as shown and described.

DESCRIPTION

FIG. 1 is a perspective view of a first embodiment of a leather lace bracelet of the present invention in a wrapped configuration.

FIG. 2 is a perspective view of the first embodiment of the leather lace bracelet of the present invention in an unwrapped configuration.

FIG. 3 is a top view of FIG. 2 of the leather lace bracelet.

FIG. 4 is a right side view of FIG. 2 of the leather lace

bracelet; the left side view is a mirror image thereof.

FIG. 5 is a bottom view of FIG. 2 of the leather lace bracelet.

FIG. 6 is a front view of FIG. 2 of the leather lace bracelet.

FIG. 7 is a rear view of FIG. 2 of the leather lace bracelet.

FIG. 8 is an enlarged portion of the circle area 8 of the

leather lace bracelet of FIG. 4.

FIG. 9 is a perspective view of a second embodiment of a leather lace bracelet of the present invention in an unwrapped configuration.

FIG. 10 is a top view of FIG. 9 of the leather lace bracelet.

FIG. 11 is a right side view of FIG. 9 of the leather lace

bracelet; the left side view is a mirror image thereof.

FIG. 12 is a bottom view of FIG. 9 of the leather lace

bracelet.

FIG. 13 is a front view of FIG. 9 of the leather lace bracelet.

FIG. 14 is a rear view of FIG. 9 of the leather lace bracelet;

and,

FIG. 15 is an enlarged portion of the circle area 15 of the leather lace bracelet of FIG. 11.

The straight line shading illustrates the smooth side of the

leather.

The stipple shading illustrates the raw side of the leather.

The broken lines represent portions of the leather lace

bracelet which form no part of the claimed design. The

dot-dash style broken lines illustrate an unclaimed boundary.

The break lines shown in FIGS. 2-5 have been included

in order to show the design at a larger scale and the design is

(Continued)

understood to continue uniformly between the break lines and be of the length shown in FIG. 1. FIGS. 9-12 also include break lines and the appearance of any portion of the article between the break lines forms no part of the claimed design.
